UNITED STATES PATENT OFFICE.

GEORGE H. KENDALL, OF NEW YORK, N. Y.

DESIGN FOR A BUSINESS-CARD.

Specification forming part of Design No. **11,255**, dated June 17, 1879; application filed April 30, 1879.
[Term of patent 7 years.]

To all whom it may concern:

Be it known that I, GEORGE H. KENDALL, of New York city, have originated a novel Design for a Business-Card, of which the following, in connection with the adjoined drawing, is a full, clear, and exact description.

The aim of my design is to provide an artistic and attractive business-card; and the annexed drawing illustrates the ornamental face of a flat card cut and printed according to my design.

The card, as shown, is of an irregular ovate shape, its perimeter or outline being sharply cut to correspond with the outer contour of a horseshoe placed slightly in perspective. The figure of a horseshoe in slight perspective is printed on the face of the card, at the margin or border, in such position as to exactly match its cut outline, as shown, while within the horseshoe, on the center of the card, is printed a landscape or picture, for which the surrounding horseshoe acts as a border or frame, as illustrated.

The cut outline of the card and the perspective position and contour of the horseshoe are such as to be symmetrical, or similar on opposite sides, as shown, thus giving a pleasing

balanced effect, and this contour and perspective position is also such that the parts corresponding to the calks of the shoe project at salient angles from the general outline of the card at top and bottom, thus giving the outline or contour of the card a more positive, varied, and attractive appearance, as illustrated.

The plain reverse side of the card is supposed to receive the printed name, address, &c., of the user, or this may be printed on a space within the horseshoe.

What I claim is—

The design for a business-card, consisting of a flat card having its border ornamented with the figure of a horseshoe placed slightly in perspective, and having its outline or perimeter cut to match with the outer contour of the said figure, the perspective position of the said figure and the cut outline of the card being symmetrical, substantially as described and illustrated.

GEORGE H. KENDALL.
